UNITED STATES PATENT OFFICE.

HOWARD E. CHAMBERS, OF LOS ANGELES, CALIFORNIA.

ADJUSTABLE HELMET AND GOGGLES.

Application filed January 13, 1925. Serial No. 2,079.

My invention relates to helmets or head gears combined with a pair of goggles, both of which are effective to protect the eyes and head of the user from the effects of light and heat in arc and gas welding, furnace work, and the like.

It has heretofore been proposed to provide a protective medium for the eyes and head of welders and other persons in similar operations, but such helmets and protective gears have been found in practice to be unhandy, and unwieldy, and have fallen far short of the purpose intended.

As will be clear, during the welding or other similar operation, it becomes necessary every so often to remove the goggles associated therewith as well as the head gear. With the devices heretofore proposed this has been an annoying feature, causing the proposed devices to be unacceptable for general use. Moreover said devices have been massive and heavy, insuring discomfort to the user. Certain of said devices also have been difficult and expensive to construct, being composed of a multitudinous number of parts. It is accordingly an object of my invention to eliminate all these objectionable features.

It is also an object of my invention to provide a novel form of adjustable helmet or head gear, capable of being adjusted to the head of the user, and which helmet has associated therewith a pair of goggles, preferably, though not necessarily, constructed of a single piece of material, said goggles being provided with a pair of lenses positioned in and secured in place in said goggles by means of adjustable bushings.

A further object of my invention is to provide a combined protective head gear or helmet having associated therewith an adjustable head band, so that said helmet or head gear may be adjusted to the head of the user, said helmet or head gear having associated therewith a pair of goggles which may be adjustably positioned over the eyes of the user, and fastened in such a position, or may alternatively be positioned over said head gear and fastened in place so that said goggles may be out of the way when not in use.

More specifically, it is an object of my invention to provide an adjustable helmet or protective head gear which has associated therewith a pair of goggles, a pair of adjustable links connecting said goggles to said hel-

met or head gear so that the distance between said goggles and said helmet or head gear may be adjusted to suit the needs of the user, it being possible to position and fasten in place said goggles over the eyes of the user, or out of the way and above said helmet or head gear.

It is also within the province of my invention to construct my novel form of helmet or head gear out of more than one piece of material, riveting or otherwise securing the various parts together, said material being preferably light, either fibre or sheet or other metal as found in practice to be desirable.

It is also within the province of my invention to form both the goggles and the head gear out of bakelite or phenol condensation product, or indeed of cast metal.

It is also an object of my invention to provide a novel form of device which is simple in character, easy and inexpensive to manufacture, durable, composed of a minimum number of parts, not easy to get out of order, and which will effectively perform the objects for which it is intended.

Further objects and advantages of my invention will become more apparent as the description thereof proceeds.

Reference is had to the accompanying drawing in which similar reference characters denote similar parts. In the drawings, Fig. 1 is a perspective view of my device, assembled and removed from the head of the user,

Fig. 2 is a similar view showing the device applied to the head of a user, with the goggles positioned over the helmet or head gear and out of use,

Fig. 3 is a front elevation of the device applied to the head of the user, the goggles being shown in operative position, and

Fig. 4 is an enlarged cross sectional view through the goggles showing the manner in which the lenses are held in position.

Describing my invention more in detail, *h* indicates the helmet or protective head gear, which may be fashioned out of any suitable material such as fibre, or any other light material, metal or otherwise, and may be cast in a single piece or constructed out of a number of parts, riveted or otherwise secured together to conform to the head of the user. As hereinbefore stated said helmet may be constructed of bakelite or phenol condensation product.

Associated with the helmet *h* is a head

band 4, which may be secured to or formed integral with said helmet, and may be provided with any sort of adjustable means such as a buckle 5, as shown in Fig. 2, so that said helmet may be adjusted to the head of the user. If desired, the front portion of said head band may be provided with a suitable padding to prevent perspiration from descending from the forehead of the user down 10 over the goggles or into his eyes.

Associated with the helmet *h* is a pair of goggles *g* preferably, though not necessarily, constructed of a single piece of material, the parts *b* of said goggles being 15 of such a configuration that the eyes of the user will be fully protected. If desired, said goggles may be constructed out of the same material as that out of which the helmet is fashioned.

20 As shown in Fig. 4, the openings of the goggles are cut away to provide circular projections on which the lenses 9 are positioned, a screw threaded bushing 7 being screwed into the framework 8 to hold 25 said lens in position. It is of course to be understood that I do not propose to be limited in this specific construction, but may in practice mount the lenses 9 in any manner found desirable.

30 To provide a means for adjusting the distance between the goggles and the helmet, so that they may be adjusted to the head of any user, and may be secured in position over the eyes of said user, and 35 fastened in such position, or alternatively may be positioned and fastened in place above said helmet and out of the way, I have provided a pair of links equipped with holes or slots to accommodate the wing nut 40 and bolt construction 2 and 3.

In operation, the helmet or protective head gear *h* is placed over the head of the user, the buckle 5 being used to adjust properly the length of the head band 4. The 45 distance between the helmet and the goggles is adjusted by means of the wing nuts and bolts. When the goggles are in use, both wing nuts 2 and 3 are turned tightly so that the goggles may not easily be displaced. Should the user desire to remove the goggles from his eyes, all that is necessary to do is to unloosen the wing nuts, quickly push the goggles over on top of 50 the helmet, where they may be secured in position almost instantly by tightening said wing nuts.

While I have described my invention with great particularity, it is clear that the same may be modified throughout a wide range. I therefore do not propose to be limited to the exact details of construction shown and described, but reserve the right in practice to make any and all modifications thereof that fall within the scope of the appended claims. 65

I claim as my invention:

1. An adjustable head and eye protector, comprising a sheet of fire resisting stiff material folded to provide a substantially rigid crown portion with rigid sides, a 70 head band secured along the lower edge of the crown portion and extending rearwardly therebeyond to encircle the head of the wearer, a pair of links pivoted to the sides of said crown portion, a pair of goggles pivoted to the free ends of the links, and means for securing the links in adjusted position about their pivotal axis. 75

2. An adjustable head and eye protector, comprising a stiff head portion having a 80 semi-crown to fit over the front top portion of the head and across the forehead and temples of the wearer and being open at the rear, a pair of links pivoted to the sides of the crown above the lower edge portions 85 thereof, a pair of goggles mounted on the free ends of the links, and means for securing the links in pivotally adjusted positions on the crown, the inherent stiffness of the crown supporting the links and goggles in 90 adjusted position.

3. An adjustable head and eye protector, comprising a helmet of stiff fire resisting material adapted to fit over the front and top of the head of the wearer, and being 95 open at the back of the head, securing means for the helmet extending from the open back thereof, a pair of links pivoted to the sides of the helmet at the forward end of the latter, a pair of goggles pivoted to the free ends of the links, said links adapted to extend vertically downward to support the goggles in front of the eyes of the wearer and adapted to be swung upwardly to position the goggles above the 100 helmet, and clamping means for the links to bind the same in adjusted positions and support the links and goggles from the stiff helmet. 105

In testimony whereof I have signed my name to this specification.

HOWARD E. CHAMBERS.
